UNITED STATES PATENT OFFICE.

JOHN LINDSAY WEBSTER, OF OTTAWA, ONTARIO, CANADA.

FUEL-SAVER AND SMOKE-CONSUMER.

1,355,370.

Specification of Letters Patent. Patented Oct. 12, 1920.

Application filed February 16, 1917. Serial No. 149,036.

To all whom it may concern:

Be it known that I, JOHN LINDSAY WEBSTER, a subject of the King of Great Britain, and residing at the city of Ottawa,

5 Province of Ontario, Dominion of Canada, have invented certain new and useful Improvements in Fuel-Savers and Smoke-Consumers, of which the following is a specification.

- 10 This invention relates to improvements in fuel savers and smoke consumers and the objects of the invention are to increase the efficiency by introducing heated air into the boiler furnace both above and below the grate thereof and simultaneously to intermix the flue gases with the required quantity of heated air, to permit of after burning taking place thereby effecting the complete combustion of the fuel.
- 15 Further objects are to readily control the stream of air delivered to the furnace and flues and generally to adapt the several parts of the boiler setting to better perform the functions required of them.
- 20 With these and other objects in view the invention consists essentially of the improved construction particularly described and set forth in the following specification and accompanying drawings forming part 25 of the same.

In the drawings,

Figure 1 is a longitudinal section of an embodiment of the present invention.

Fig. 2 is a transverse section on the line 35 2-2 of Fig. 1.

Fig. 3 is a transverse section on the line 3-3 of Fig. 1.

Fig. 4 is a sectional plan view on the line 4-4 of Fig. 2.

40 Fig. 5 is a fragmentary perspective view of the bridge wall and side wall of the furnace showing the location of the several air passageways and the manner in which they communicate with the chamber in the bridge wall.

Fig. 6 is a front elevation of a boiler setting showing the perforated front plates through which the air enters.

Fig. 7 is a longitudinal section of an 50 alternative form of the invention.

Like characters of reference refer to like parts in the several figures.

Referring to the drawings, A represents a boiler of any usual description provided 55 with a plurality of tubes 10 extending therethrough, the said boiler being supported by

the hangers 11 suspended from the transversely extending I-beams 12 carried by the side walls 13 of the masonry inclosing the boiler.

60

Chambers 14 and 15 are provided at the front and rear ends of the boiler A, the latter communicating with a smoke stack and being separated from the combustion chamber 16 by the wall 17 which engages with 65 the rear end of the boiler.

The combustion chamber 16 communicates with the furnace B but is separated therefrom by the bridge wall C having a compartment or chamber 18 therein filled with 70 checker brick work which provides a baffling means and exposes an enlarged heating area to the air which is caused to pass through the said chamber in a manner to be made clear hereafter.

75

The furnace B is located centrally below the boiler A at the forward end thereof but the grate does not extend the full width of the space below the boiler, the side walls 19 of the furnace being spaced from the side 80 walls 13 of the masonry to form flues 20 through which the gases from the furnace are designed to pass.

The front ends of the flues 20 communicate with the chamber 14, while the rear ends open into the combustion chamber 16 so that the products of combustion after leaving the furnace B pass by way of the combustion chamber 16 into the flues 20, from whence they are delivered to the chamber 14 and after passing through the tubes 10 into the chamber 15 are delivered to the smoke stack.

90

The side walls 19 of the furnace are provided with longitudinally extending conduits 21 which are located below the grate of the furnace B and are provided with a plurality of discharge orifices 22 through which air is delivered into the ash-pit D, which is of the closed type.

95

The rear ends of the conduits 21 communicate through the opening 6 with the chamber 18 in the bridge wall which further communicates by means of the conduit 9 with the air passageway 23 extending through the crest of the side walls 19 of the furnace, 100 the said passageways being provided with a plurality of discharge orifices 24, which deliver hot air into the furnace B.

100

Conduits 25 extend longitudinally of the side walls 13 and communicate through the 110 passageway 26 (shown in Fig. 4) with the chamber 18 in the bridge wall, the said con-

duits being provided with a plurality of discharge orifices 27 through which heated air is delivered into the flues 20 to intermix with the gases passing therethrough.

- 5 Air is delivered to the chamber 18 in the bridge wall C through the inlet passages 28 which extend from the front of the boiler rearwardly below the flues 20 and communicate with the chamber 18 through the passage 29 shown in Fig. 4, the stream of air delivered to the said inlet passages being controlled by a grid or grating 8 or other suitable valve means.

To facilitate cleaning doorways 30 and 31 are provided through which access to the chamber 15 and the combustion chamber 16 is obtained.

In Fig. 7 an alternative form of the invention is set forth which only differs from 20 that form already described in the provision of a heating chamber E provided at the rear end of the brick work or masonry, the said chamber communicating through the passageway 32 with the chamber 18^a in the bridge wall C¹.

Air is supplied to the chamber E from the front of the masonry by passing through the perforated front plate such as is shown in Fig. 6 into the passageway 28^a which extends rearwardly and discharges into the heating chamber E so that the air entering the passageway 28^a is caused to flow for practically the whole length of the boiler rearwardly, where it is delivered into the passageway E and forwardly through the passage 32 into the chamber 18^a in the bridge wall C¹ from whence it is delivered to the air passageways or conduits 25, 21 and 23 as illustrated in Fig. 5.

40 In the embodiment illustrated in Fig. 7, conduits 25 in the side walls 18 are connected by a transverse conduit 25^a extending through the transverse walls 17, so that in this case a U-shaped passageway is provided 45 and pre-heated air is delivered through the orifices 27 into the flues 20 and into the combustion chamber 16 on three sides of the said combustion chamber, namely on the sides and rear thereof, so that the products 50 of combustion entering the chamber 16 will be ultimately mixed with heated air and thus the combustion of the fuel will be completed.

The assembly of the several parts of the 55 structure will be readily understood from the foregoing description.

When a boiler set in the above manner is in use, the valve means controlling the inflow of air through the passageways 28 is 60 regulated and the air on its way through the said passageways becomes heated from the furnace walls 19 and flues 20.

This air passes through the passageway 29 into the chamber 18 in the bridge wall

C where it comes under the influence of the 65 heating surface of the checker brickwork filling the said chamber, and the heated air is now delivered through the opening 6, passageway 26 and conduit 9 to the conduits and passageways 21, 25 and 23 as illustrated in Fig. 5, where it is delivered to the furnace below and above the grate thereof and also into the flues 20.

As the products of combustion pass through the furnace and over the bridge 75 wall they intermix with the heated air delivered through the openings 24 in the passageway 23 into the said furnace and combustion chamber, so that a further burning of the products of combustion takes place 80 with the generating of greater heat.

When the furnace gases enter the combustion chamber 16 they are subdivided into two streams which are delivered to the flues 20 where they are again intermixed with hot air issuing from the orifices 27 in the conduits 25, so completing the combustion and the products of combustion which now pass through the tubes 10 from the chamber 14 are at an extremely high temperature and 90 are then delivered to the chamber 15 and thence to the uptake, and the said products of combustion on their passage rearwardly, forwardly, and then again rearwardly of the boiler, effectively heat the water in the 95 boiler.

In that form of the invention illustrated in Fig. 7, the same action as that already described takes place, except that in this case the heated air is delivered to the chamber 16 on three sides thereof from the passageways 25, and also from the conduit 25^a passing through the division walls 17, and by the use of the heating chamber E a larger volume of air is heated to the desired temperature, as the air is kept for a somewhat longer period in contact with the heated brick work or masonry in its setting in its passage through the passageway 28^a, chamber E and passageway 32 before entering 100 the compartment or chamber in the bridge wall C¹.

The doors and other usual appliances on the front of the furnace have either been omitted or not described as they would 115 only detract from the clearance in illustration and description of the invention.

While in the embodiment illustrated the air is delivered to the inlet passageways 28 under a natural draft, it will be understood 120 that a blower or steam jets may be utilized for inducing this flow of air when such is found desirable or necessary.

It will be readily seen that the air prior to discharging into the furnace gases is thoroughly heated by its passage through the several conduits and chamber in the bridge wall and the air thus intermixed with the

furnace gases will produce a secondary combustion and effect an economy in fuel and eliminate smoke.

As many changes could be made in the above construction and many apparently widely different embodiments of my invention, within the scope of the claim, constructed without departing from the spirit or scope thereof, it is intended that all matter contained in the accompanying specification and drawings shall be interpreted as illustrative and not in a limiting sense.

What I claim as my invention is:

In a fuel saver, a boiler setting including side walls, furnace side walls spaced from the said side walls to form flues, a bridge wall extending transversely between the furnace side walls, a furnace in front of the bridge wall, a combustion chamber behind the bridge wall, a boiler forming a closure for the upper portion of the furnace and the

combustion chamber, means for closing the space between the boiler and the said side walls, a chamber in the bridge wall, air conduits in the furnace wall above and below a 25 grate of the furnace, the said conduits communicating with the chamber in the bridge wall, conduits in the side walls communicating with the flue between the said walls and the furnace side walls, the said conduits communicating with the chamber in the bridge wall, air inlet conduits extending below the said flues, the front ends of the conduits extending through the front of the setting, and the rear ends communicating with the chamber in the bridge wall, and damper means controlling the flow of air through the said air conduits.

In witness whereof I have hereunto set my hand.

JOHN LINDSAY WEBSTER.
